UNITED STATES PATENT OFFICE.

WILLIAM H. PARKER, OF MABEN, MISSISSIPPI, ASSIGNOR OF ONE-HALF
TO CHARLES N. RIX, OF HOT SPRINGS, ARKANSAS.

LOCK-WASHER FOR NUTS.

SPECIFICATION forming part of Letters Patent No. 784,423, dated March 7, 1905.

Application filed December 17, 1904. Serial No. 237,333.

To all whom it may concern:

Be it known that I, WILLIAM H. PARKER, a citizen of the United States, residing at Maben, in the county of Okfobbeha and State of Mississippi, have invented certain new and useful Improvements in Lock-Washers for Nuts; and I do hereby declare the following to be a full, clear, and exact description of the invention, such as will enable others skilled in the art to

10 which it appertains to make and use the same.

My invention relates to improvements in locks for nuts, adapted more particularly for use on railroads, &c. It has for its object to provide a single lock of the same type as the 15 double washer for which I made application, Serial No. 193,385, on February 13, 1904, which is simple and cheap of manufacture and at the same time will not easily get out of order, but will securely and permanently hold 20 the nut against displacement.

The invention consists in the details of construction and combinations of parts herein-after described, and more particularly pointed out in the claims concluding this specification.

25 In the accompanying drawings, illustrating the preferred embodiment of my invention, Figure 1 is a plan view of a washer-plate made in accordance with my invention. Fig. 2 is an edge view thereof, and Fig. 3 is a perspective view of one of said washers attached to a section of framework.

While the preferred embodiment of my invention is fully shown in the accompanying drawings and its construction and operation 35 are clearly described in this specification, I reserve the right to make such changes from the construction shown and described herein as the scope of the claims hereunto appended will permit.

40 In carrying out my invention I provide a curved or bowed plate, preferably of spring metal, having a perforation for the passage of a bolt, and a lip formed by cutting a slit from its lateral edge inward and thence a longitudinal slit, said lip turned up laterally substantially perpendicular with the plate, the bend extending from the extremity of the 45 longitudinal slit to a point on the edge within

the ends of said plate. Said plate is also provided with means for securing it against rotation, preferably consisting in forming points adapted to enter the wood of the article to which it is attached by turning down the corners of said plate. The lip is adapted to be pressed outward by the corners of the nut as 50 it is turned on, and when the plate is made of spring metal said lip springs back at each step and locks the nut against reverse turning. The plate may be made of soft iron or other metal, in which case the lip would have to be 55 manually pressed back into position to lock the nut after it has been screwed "home."

Referring more particularly to the drawings, 1 is the washer-plate, and 2 is the lip, formed by cutting a lateral slit 3 from its edge 60 and a longitudinal slit 4. The bend of said lip is indicated at 5 and extends from the end of the longitudinal slit to the point 6 on its lateral edge. The corners of the plate are turned down, as at 7, and are adapted to be 65 pressed into the surface of the article to which said plate is applied to secure the plate against rotation.

It is obvious that other suitable means may also be used to hold the plate from turning. 70 When the plate is made of spring metal, the tension of the spring when depressed by screwing down the nut adds materially in securing the nut in position and takes up the wear on the parts and the elongation of the 75 bolt. My lock is particularly adapted for use in railway-car construction; but it may be used to advantage in many other places.

Having thus described my invention, what I claim as new, and desire to secure by Letters 80 Patent, is—

1. In a device of the character described, a washer-plate having a lip formed by cutting a slit from its lateral edge inward and thence a longitudinal slit, said lip turned up laterally substantially perpendicular with the plate, the end of said lip adapted to engage the side of a nut at right angles thereto and lock said nut against reverse turning.

2. In a device of the character described, a washer-plate having a lip formed by cutting

a slit from its lateral edge inward and thence a longitudinal slit, said lip turned up laterally substantially perpendicular with the plate, the end of said lip adapted to engage the side 5 of a nut at right angles thereto and lock said nut against reverse turning, and means for holding the plate against rotation.

3. In a device of the character described, a curved washer-plate having a lip formed by 10 cutting a slit from its lateral edge inward and thence a longitudinal slit, said lip turned up laterally substantially perpendicular with the plate, the end of said lip adapted to engage the side of a nut at right angles thereto and 15 lock said nut against reverse turning.

4. In a device of the character described, a washer-plate of spring metal having a lip formed by cutting a slit from its lateral edge inward and thence a longitudinal slit, said lip turned up 20 laterally substantially perpendicular with the plate, the end of said lip adapted to engage the side of a nut at right angles thereto and lock said nut against reverse turning.

5. In a device of the character described, a washer-plate having a lip formed by cutting a slit from its lateral edge inward and thence a longitudinal slit, said lip turned upward laterally substantially perpendicular with the 25 plate, the bend extending from the extremity of the longitudinal slit to a point on the edge within the ends of said plate, said lip adapted

to engage the side of a nut and lock said nut against reverse turning.

6. In a device of the character described, a 35 washer-plate having a lip formed by cutting a slit from its lateral edge inward and thence a longitudinal slit, said lip turned upward laterally substantially perpendicular with the plate, the bend extending from the extremity 40 of the longitudinal slit to a point on the edge within the ends of said plate, said lip adapted to engage the side of a nut and lock said nut against reverse turning, and means for holding the plate against rotation. 45

7. In a device of the character described, a washer-plate of spring metal having a lip formed by cutting a slit from its lateral edge and thence a longitudinal slit, said lip turned upward laterally substantially perpendicular 50 with the plate, the bend extending from the extremity of the longitudinal slit to a point on the edge within the ends of said plate, said lip adapted to act as a ratchet against the corners of the nut permitting it to be turned 55 on and locked against reverse turning, and means for holding the plate against rotation.

In testimony whereof I affix my signature in presence of two witnesses.

WILLIAM H. PARKER.
